US0D1103389S

(12) **United States Design Patent** (10) **Patent No.:** **US D1,103,389 S**
(45) **Date of Patent:** **** Nov. 25, 2025**

(54) **SUPPORT SYSTEM FOR TREATMENT DEVICE**

(71) Applicant: **Avava, Inc.**, Waltham, MA (US)

(72) Inventors: **Jayant Bhawalkar**, Auburndale, MA (US); **Ryan Martin**, Carlisle, MA (US); **Patrick Shaughnessy**, Boston, MA (US); **Lewis Levine**, Marlborough, MA (US); **Andrew Ziegler**, Arlington, MA (US); **Michael Stephen Rafferty**, Madison, WI (US); **Zachary Michael Zlevor**, La Grange Park, IL (US)

(73) Assignee: **Avava, Inc.**, Waltham, MA (US)

(**) Term: **15 Years**

(21) Appl. No.: **29/873,935**

(22) Filed: **Apr. 11, 2023**

(51) LOC (15) Cl. **24-02**

(52) U.S. Cl.

USPC **D24/183**

(57) **CLAIM**

The ornamental design for a support system for treatment device, as shown and described.

DESCRIPTION

FIG. 1 is a perspective view of a new design of a support system for treatment device;

FIG. 2 is a front view of the support system for treatment device of FIG. 1;

FIG. 3 is a back view of the support system for treatment device of FIG. 1;

FIG. 4 is a left view of the support system for treatment device of FIG. 1;

FIG. 5 is a right view of the support system for treatment device of FIG. 1;

FIG. 6 is a top view of the support system for treatment device of FIG. 1; and,

FIG. 7 is a bottom view of the support system for treatment device of FIG. 1.

The broken lines depict portions of the support system for treatment device that form no part of the claimed design.

1 Claim, 5 Drawing Sheets
